UNITED STATES PATENT OFFICE.

GEORGE B. HOYT, OF CLEVELAND, OHIO, ASSIGNOR TO THE NATIONAL COMPUTING SCALE COMPANY, OF SAME PLACE.

DESIGN FOR A FACE-PLATE FOR SCALES.

SPECIFICATION forming part of Design No. 30,724, dated May 9, 1899.

Application filed June 16, 1898. Serial No. 683,648. Term of patent 14 years.

To all whom it may concern:

Be it known that I, GEORGE B. HOYT, a citizen of the United States, residing at Cleveland, in the county of Cuyahoga and State of Ohio, 5 have invented and produced a new and original Design for Face-Plates for Scales, of which the following is a specification, reference being had to the accompanying drawings, forming a part thereof.

10 Figure 1 is a front elevation of a face-plate, showing my new design; and Fig. 2 is a sectional view taken on the line 2 2 of Fig. 1.

As shown in the drawings, the leading or material features of my design consist of a 15 circular plate having near its periphery an elongated opening, one side of which is a curve substantially concentric with said periphery and the ends of which are curves and

the other side of which has a pointed lip extending into the opening, this pointed lip being nearer one end of the opening and one of its sides making a substantially continuous curve with that end of the opening. A represents the face-plate, B the arc-shaped opening, and C the pointed lip.

Having described my invention, what I claim, and desire to secure by Letters Patent, is—

The design for a face-plate for a scale, as herein shown and described.

In testimony whereof I hereunto affix my signature in the presence of two witnesses.

GEORGE B. HOYT.

Witnesses:

PHILIP E. KNOWLTON,
E. L. THURSTON.
